CLOGGED DRAIN FLUSHING DEVICE

Charles Davis, Los Angeles, Calif.

Application April 30, 1946, Serial No. 666,056

3 Claims. (Cl. 4—256)

1

This invention relates to a device adapted to cleaning drain pipes and more particularly has as an object the provision of an apparatus especially applicable in flushing out clogged drain pipes associated with sinks, laundry tubs and the like.

Other objects and advantages of the invention will be apparent from the following description and claims, the novelty consisting in the features of construction, combination of parts, the unique relations of the members and the relative proportioning, disposition and operation thereof, all as more completely outlined herein and particularly pointed out in the appended claims.

Referring to the drawings which form part of the specifications:

Figure 1 is a perspective view of my device in position to effect flushing of the clogged drain pipe of a sink.

Figure 2 is a side elevational view partly in section of my device in operative position; and

Figure 3 is a sectional view of the swivel attachment for the end of the lever arm of the device.

My improved device is based on a horizontal lever 10 inserted through an aperture of a resilient or flexible T-fitting 12 and adapted to urge at right angles thereto, an operating rod 14 connected at one end to the T-fitting and at the other end to a flexible cup 16, adapted to encircle the mouth of a drain 17 of a sink or wash basin 18, or the like. Location of the T-fitting along the lever 10 serves to delineate upon the latter a longer and a shorter lever arm, 19 and 20 respectively, on opposite sides thereof.

A flexible conduit or rubber hose 21, of conventional design, is frictionally attached to a nipple 22 disposed at one side of the flexible cup, the other end of said hose being adapted for connection to the outlet of a water faucet 24, so that the full stream of water from the faucet may be thus directed down the drain with undiminished pressure through the attached hose and cup.

The lever 10 is provided with a suitable handle 26 on its longer arm and a gripping attachment 28 at the terminal end of its shorter arm. The gripping attachment is adapted for temporary bearing on a water faucet 30, or other stationary object by reason of two angularly disposed arms 32 and 34, arranged to engage opposite faces of the horizontal portion of the faucet, the arms being provided with a surface covering 35 of rubber or other suitable non-marring material.

The engaging arms 32 and 34 are formed in-

2

tegral with a swivel 36 which is operatively mounted in the upturned end of an elbow 38 by means of a lateral pin 40 inserted jointly along one side of a circumferential groove 42 of the swivel and through an aligned aperture of the elbow.

The elbow 38 is in turn mounted on the end of the shorter lever arm 20, so that the lever may be thus quickly attached to the faucet to provide a fulcrum for exerting downward pressure on the flexible cup 16 as shown by the broken lines of Figure 2, thereby insuring that none of the water passing through the hose 21 is permitted to enter the surrounding sink or basin 18.

In this connection, it is important to note that precise alignment of the cup 16 with the mouth of the drain 17, is effected by reason of the fact that both the cup 16 and the T-fitting 12 are made flexible, being conveniently formed of rubber or other suitable material.

Such construction compensates both for unevenness of the horizontal surface around the drain mouth and for differences of the vertical distance between various faucets and their respective sinks. Also the provision of a comparatively large circumference cup 16 permits interchangeable employment of the device for sinks having various size drain openings. Likewise the operating rod 14 may be of varied length corresponding to diverse depths of sinks and laundry tubs, etc.

When the lever is tilted to press cup 16 over outlet 17, the T-fitting 12 will be distorted so as to prevent said lever from moving lengthwise therethrough.

Further, as the fitting 12 and cup 16 are formed of resilient material, said lever and post will tend to automatically adjust themselves to the fixed parts on which they bear and to the strains that press the cup against the bottom of the bowl.

While I have shown and described in some detail a presently preferred embodiment of my drain flushing device, it is to be understood that various modifications may be made in the construction and operation thereof within the scope of the subsequently claimed invention, which is to be construed broadly and limited only by the prior art.

50 I claim as my invention:

1. A device for flushing drains and the like including a generally horizontally disposed lever having a pair of angularly directed engaging arms swivelly mounted at one end thereof substantially at right angles to said lever, a flexible

T-fitting having said lever inserted through an aperture thereof, a flexible cup-like member adapted to encircle the mouth of a drain, an operating rod connected at one end to said T-fitting substantially opposite to and longitudinally spaced from said engaging arms and connected at its other end to said cup-like member, and conduit means for conveying liquid under pressure to the interior of said cup-like member.

2. A clogged drain flushing device comprising a head lever, a resilient T-fitting adjustably mounted on said lever, a post detachably connected to said T-fitting, a resilient inverted cup shaped member detachably connected to the lower end of said post, and means for delivering

water under pressure to said inverted cup-shaped member.

3. A clogged drain flushing device as set forth in claim 2, with an elbow mounted on the distal end of said lever and a V-shaped member mounted for rotation in said elbow.

CHARLES DAVIS.
